[57] CLAIM

The ornamental design for a compressed air sprayer tank, substantially as shown.

DESCRIPTION

FIG. 1 is an isometric view taken from the front and left side of a compressed air sprayer tank showing our new design;

FIG. 2 is a rear elevational view thereof;

FIG. 3 is a right side elevational view thereof;

FIG. 4 is a top plan view thereof; and

FIG. 5 is a bottom plan view thereof.

The broken line representation of a supply tube in FIGS. 1 and 2 is for purposes of illustration only.

FIG. 1

FIG. 2

FIG. 3

FIG. 4

FIG. 5
